UNITED STATES PATENT OFFICE

WILLIAM D. FERRIS, OF STERLING, ILLINOIS, ASSIGNOR TO HUSTLER TOY CORPORATION, OF STERLING, ILLINOIS, A CORPORATION OF ILLINOIS

MECHANICAL TOY DEMONSTRATOR

Application filed October 31, 1929. Serial No. 403,724.

This invention relates to demonstrators for mechanical toys, and more particularly to devices for demonstrating mechanical toys having vehicle wheels adapted to travel on the floor.

Generally stated, the object of the invention is to provide a demonstrator which will enable the wheeled mechanical toy to remain stationary in one position, but which will operate the vehicle wheels of the toy, and other parts thereof, thus simulating the natural or ordinary use or operation of the toy.

It is also an object to provide certain details and features of construction and combinations tending to increase the general efficiency and the desirability of a toy demonstrator of this particular character.

To the foregoing and other useful ends, the invention consists in matters hereinafter set forth and claimed and shown in the accompanying drawings, in which—

Fig. 1 is a front elevation of a mechanical toy demonstrator embodying the principles of the invention;

Fig. 2 is a plan view of the said demonstrator, being in the nature of a horizontal section on line 2—2 in Fig. 1 of the drawings.

As thus illustrated, the invention comprises a housing 1, provided with a stage opening 2 having a curtain 3, as shown. The floor of the stage is provided with an endless conveyor 4 mounted on rolls 5 and 6, this endless conveyor being in the form of a belt, for supporting the toy 7, which latter is of any suitable or desired form, but preferably has vehicle wheels 8 that rest on said endless conveyor belt. Thus the broad flat belt is operable with toys having the wheels differently located thereon.

Said belt is driven by a motor 9 through the medium of a sprocket chain 10, this sprocket chain or belt being mounted on sprocket wheels 11 and 12, secured respectively, to the shafts 13 and 14, as shown. The shaft 13 is operated by the motor 9, through any suitable power-transmitting connection, and the shaft 14 carries the roll 6, previously mentioned.

A roll-tightening device is provided, comprising adjusting screws 15 and 16, these screws being arranged to adjust the shaft 14

toward and away from the other shaft 17, upon which the roll 5, previously referred to, is mounted. In this way, the conveyor belt 4 is maintained in proper condition to support the said mechanical toy.

An electrical lamp 18 is preferably provided over the stage behind the upper portion of the curtain 3, and the circuits for this lamp, and for the previously mentioned motor 9, are controlled by an ordinary hand-switch 19 of any suitable or desired character. In this way, when the switch 19 is closed, the motor 9 is started, the electrical lamp 18 is lighted, and the belt 4 is operated by the roller 6 to thereby rotate the wheels 8 of the mechanical toy, and in this way other portions of the toy are operated, depending upon the character thereof.

It will be seen that the motor 9 and the connections therefrom to the shaft 14 are not below the endless belt conveyor 4, but, to the contrary, are in a chamber disposed in the rear of said belt in the rear portion of the housing 1, while the stage proper, including the conveyor 4, is at the front of the housing 75 and immediately inside of the stage opening 2 formed in the front wall of the housing.

Of course, some provision must be made for holding the toy 7 stationary, during the operation of the wheels and other parts thereof, and such provision is preferably adjustable for toys of different lengths. For example, the stage floor can be provided with two rows of holes 20, and a cross strip 21 can be provided for adjustment along said holes, said cross strip having a slot 22 for one of the wheels 8 of the toy, whereby this wheel will rest on the belt 4 and be rotated. Pins 23, inserted through holes in the cross piece 21 and into some of the holes 20, may be employed for holding the cross piece 21 in adjusted position. For other toys, having differently arranged wheels, other cross strips can be employed, similar to the cross strip 21, these other cross strips (not shown) having one or more slots arranged in each case for some specific form of toy.

Thus, the invention contemplates a mechanical toy demonstrator having a support for the vehicle wheels of the toy, with means

to hold the toy stationary, and means to rotate one or more wheels of the toy, thereby to simulate the ordinary operation of the toy, preferably in combination with instrumentalities for simulating a stage having a more or less attractively ornamented front and an opening therein to display the toy.

What I claim as my invention is:

1. In a mechanical toy demonstrator, adapted for demonstrating different wheeled toys, which toys are mechanically operative independently of said demonstrator, on any smooth floor, and are adapted to be sold separately as such, the combination of means for supporting and operating one or more of the vehicle wheels of the toy, means for communicating operating power to said supporting means, and wheel contacting means extending transversely over the supporting and operating means, directly across the path of the wheel or wheels of the toy, to hold the toy stationary in a position suitable for each toy during the operation of the wheel or wheels thereof, said wheel contacting means having separable contact with the toy, whereby the toy may be removed and placed on any floor.
2. A structure as specified in claim 1, said supporting means comprising an endless belt forming a movable platform for the toy.
3. A structure as specified in claim 1, said supporting means comprising an endless belt forming a movable platform for the toy, having a flat surface for contact with the wheels, so that the toys may have wheels differently located thereon, and said means for communicating power comprising an electric motor having a power-transmitting connection to said belt.
4. A structure as specified in claim 1, said supporting means comprising an endless belt forming a moving platform for the toy, having a flat surface for contact with the wheels, so that the toys may have wheels differently located thereon, and said means for holding the toy stationary comprising a cross piece for engaging one or more wheels of the toy, while permitting such wheel or wheels to rotate.
5. A structure as specified in claim 1, said supporting means comprising an endless belt forming a moving platform for the toy, having a flat surface for contact with the wheels, so that the toys may have wheels differently located thereon, and said means for holding the toy stationary comprising a cross piece for engaging one or more wheels of the toy, while permitting such wheel or wheels to rotate, together with means permitting adjustment of said cross piece longitudinally of said belt for different toys.
6. A structure as specified in claim 1, in combination with instrumentalities for simulating a stage, with said supporting means

forming the stage floor, and with a stage opening in front to fully display the toy.

7. A structure as specified in claim 1, comprising instrumentalities forming a housing to simulate a stage, with said supporting means forming the stage floor, with space below the stage, and with a chamber in rear of the space below the stage floor to enclose said means for communicating power to the supporting means.

8. A structure as specified in claim 1, comprising instrumentalities for simulating a stage having an opening to display the toy, with said supporting means forming the stage floor, an electric lamp at the top of said stage opening, said means for communicating power to said supporting means comprising an electric motor, with a single switch for controlling the circuits of both said lamp and motor.

Specification signed this twenty-eighth day of October, 1929.
